UNITED STATES PATENT OFFICE.

LEWIS C. MYERS, OF BROOKLYN, NEW YORK, ASSIGNOR TO ROYAL TYPEWRITER COMPANY, INC., OF NEW YORK, N. Y., A CORPORATION OF NEW YORK.

PAPER TABLE AND GAGE.

1,282,454.

Specification of Letters Patent. Patented Oct. 22, 1918.

Application filed May 1, 1917. Serial No. 165,61

To all whom it may concern:

Be it known that I, LEWIS C. MYERS, a citizen of the United States, and a resident of the borough of Brooklyn, in the city of New York, county of Kings, and State of New York, have invented certain new and useful Improvements in Paper Tables and Gages, of which the following is a specification.

10 The present invention relates generally to typewriting or other machines of the same general character and has more particularly reference to a paper table or page gage for side registering the material acted upon by 15 the machine.

In the Hess Patent No. 958,497 there is disclosed a typical structure of writing machine in connection with which the present invention may be conveniently used. As 20 there shown, a platen is used with which is associated a support usually carrying the paper pan, and a paper table which can be tilted upwardly and rearwardly on a pivot remote from the platen. When the paper 25 table is in its lowered position it rests on the support and with it forms a substantially continuous upwardly inclined paper surface. With this construction when the paper is adjusted backward it will be guided upwardly 30 in a proper manner and without any tendency to enter between the support and the paper table.

The main object of this invention is to provide means whereby gaging of the paper 35 can be obtained in close proximity to the platen in such a manner that the parts may be readily accessible when the paper table is swung out of the way. This is especially advantageous when a short sheet length of 40 paper is being adjusted in the machine.

Other objects will appear as the specification proceeds.

One feature of the invention resides in providing a cut-out portion in the upwardly 45 inclined paper surface, at which point is located means for supporting or mounting a laterally movable paper gage. In the preferred form herein disclosed said cut-out portion is located intermediate the support 50 and the paper table. In the more specific form embodying the invention which is herein disclosed, said cut-out portion is preferably arranged on a tiltable paper table, and

the support for the gage is likewise carried by said table and tiltable therewith. 55

Another feature of the invention resides in having a laterally sliding paper gage which normally overlies both the support for the paper pan and the paper table, said gage being, in the preferred construction herein disclosed, tiltable with the paper table.

A still further feature of the invention resides in the construction of the paper table. This table is of sheet material and has a 65 rolled-over portion which forms an integral tubular member, there being a rod in said tubular member and a paper gage carried by the rod. Any suitable means may of course be used for rendering the paper gage 70 laterally adjustable, but, in the preferred form herein shown, the rod is slidable in the tubular member and the paper gage is fixed to the rod. Preferably also there are provided means for preventing the rod from 75 turning in the tubular member, and sufficient friction, to hold the rod in its correct adjusted position, may be obtained by any suitable means, such as by splitting the end of the rod and causing it to expand slightly. 80 The rolled-over portion of the paper table is preferably produced by having an extension that projects beyond the lower edge of the paper table and is then rolled over so that the gage which slides in said rolled over 85 portion may be adjusted along said lower edge. In the particular embodiment of the invention herein shown, the rolled-over portion is disposed centrally of the lower edge of the paper table and has a rod projecting 90 from each end, together with a paper gage mounted on each rod so that gaging may be obtained at both side edges of the paper.

In the accompanying drawings the invention is embodied in several preferred forms 95 and in these drawings:

Figure 1 is a face view of a paper table and a support embodying the invention, together with the means for supporting the paper table preferably carried by the tabular bar in a known manner.

Fig. 2 is a vertical sectional view on the line 2-2 of Fig. 1.

Fig. 3 is a broken view, partly in section, showing the lower portion of the rear of the 105 paper table.

Fig. 4 shows a modified form of the invention and is a fragmentary view showing a portion of the paper table, in this instance provided with coiled portions both at its upper and lower ends and with rods, carrying a gage, working in both of said coiled portions.

Fig. 5 is a vertical sectional view on the line 5—5 of Fig. 4.

10 Fig. 6 is an end elevation of the paper table and support partly in section showing also the platen and the pivot on which the paper table swings and illustrating the close proximity of the paper gage to the platen, together with the arc described by the end 15 of the said paper gage when the paper table is tilted rearwardly and upwardly.

7 is the usual support which carries the paper pan and 8 is the paper table. The 20 paper table is suitably mounted by means of arms 9 which in this case are conveniently pivoted on the end of the tubular bar 10 and which have lugs 11 parallel to the paper table and secured thereto in any suitable 25 manner, such as by means of the screws 12. When the paper table is in its lowermost position, which is the position that it normally occupies during the manipulation of the writing machine, this lower edge rests 30 upon the top of the support 7 and the two together form substantially a continuous upwardly inclined paper surface for guiding the paper. The engagement of the paper table 8 with the support 7 is preferably so 35 intimate that if the paper is manipulated backwardly in the machine its free end will not enter between said support and paper table but will be guided upwardly in the proper manner. The paper table is preferably 40 made of sheet material, as shown, and is provided at its lower edge with cut-out portions 13 preferably at both ends, while at its central lower portion it is provided with a coiled portion forming a tubular member 14 as shown. The result is that 45 when the paper table is lowered into contact with the support 7, the said coil 14 will rest upon the upper surface of the said support. 50 15 indicates a rod which is slidably mounted in the coil 14 and preferably has its inner end 16 split, as shown, so as to produce sufficient friction to retain said rod in any adjusted position in which it may be placed. Carried by this rod 15 is a paper gage 16 55 which is here shown as consisting of a portion 17 substantially parallel to the upwardly inclined paper surface and which further has an outwardly projecting portion 18 at an angle thereto which extends over 60 toward the platen 19 and in close proximity thereto. The paper gage is thus carried by the paper table and is tilttable therewith. When the paper table is in its lowered position the paper gage overlies both the support 65 7 and the paper table 8, as shown. The ad-

vantage of this is that by that means it is brought into close proximity so that short sheet lengths may be adjusted at a point very close to the platen and also should the material be manipulated backwardly 70 through the machine said gage will afford a bridging member over the cut-out portions 13 so that the paper will not take the wrong path. The paper gage 16 is secured to the rod 15 in any suitable manner, such 75 as by soldering, and preferably has a rear wing 20 which passes up on the rear side of the paper table. In this manner the portion 17 and the rear wing 20 form a guide that virtually slides on the lower edge 13 of 80 the paper table and also at the same time keeps the gage from tilting by preventing a turning movement of the rod 15 within the tubular member 14. From Fig. 6 it will be seen how closely adjacent the paper gage is 85 to the platen when the paper table is in its lowered position, and it will also be seen that the paper table may be raised or tilted without interference since the lowermost tip of the gage will describe substantially the arc 90 indicated in dotted lines. In order to insure the closest possible approach of the gage to the platen, the lower end 21 of the outwardly extending portion 18 of the paper gage is beveled or inclined, as shown. 95

In Figs. 4 and 5 a modification is shown. In this instance the paper table 8 is provided with a coiled tubular portion 22, both at its upper and lower edge. Into these coiled tubular portions extend the rods 23 which are slidably mounted and carry at their outer ends the gage 24. In this instance the paper table 8 is provided with rearwardly extending lugs 25 to which tilting arms similar to 9 on Fig. 1 may be secured. In the form shown in Figs. 4 and 5 it will be seen that the gage does not overlie both the paper table and the support but is, nevertheless, within the scope of the invention, so far as the feature of utilizing tubular portions on the paper table for the purpose of mounting a paper guide is concerned. 105 110

If desired, a suitable indicating means such as a scale or index may be utilized in connection with the paper gage and such scale or index may be carried either by the support 7 or by the paper table 8 or by both. In Fig. 1 the scale 26 is shown as being arranged both on the support 7 and on the 120 paper table 8. The advantage of having the scale on the paper table is that it permits adjustment of the gage 17 when the paper table is in its tilted position. In Fig. 4, the scale 27 is shown arranged on the paper 125 table.

While the invention has been described in connection with one gage only, it is clear from Fig. 1 that if desired a double arrangement may be provided and a gage 16 may 130

be mounted at each end of the paper table with separate rods 15 extending into the common central tubular member 14.

I claim:

5. 1. A platen, a substantially continuous paper surface, upwardly inclined from said platen, including a support, closely adjacent to the platen, and a paper table tiltable rearwardly and upwardly on a pivot remote 10 from said platen, resting on the upper edge of the support when in its lowered position, a paper gage laterally slidable and tiltable with the table, having a portion substantially parallel to the paper surface normally 15 overlying both the table and the support, and an outwardly projecting portion extending closely adjacent to the platen when the paper table is in its lowered position.
2. A paper table of sheet material having 20 an extension projecting beyond its lower edge and rolled over to form a tubular member, a paper gage laterally adjustable along said lower edge, and means carried in said tubular member for supporting said gage.
3. A paper table of sheet material having 25 an extension projecting beyond its lower edge and rolled over to form a tubular member, a rod slidable in said tubular member, and a paper gage carried by said rod.
39. 4. A paper table of sheet material having 30 an extension projecting beyond its lower edge at the central portion thereof and

rolled over to form a tubular member, a paper gage at each end of the tubular member laterally adjustable along said lower 35 edge, and means carried in said tubular member for supporting said gage.

5. A paper table of sheet material having an extension projecting beyond its lower edge at the central portion thereof and rolled 40 over to form a tubular member, a rod projecting from each end of said tubular portion, and a paper gage mounted on each rod.

6. A paper table of sheet material having an extension projecting beyond its lower 45 edge at the central portion thereof and rolled over to form a tubular member, a rod slidably mounted in each end of the tubular portion, and a paper gage on each rod.

7. A platen, a substantially continuous paper surface upwardly inclined from said platen, including a support adjacent the platen, a paper table, means for rearwardly 55 tilting said paper table, a laterally sliding paper gage tiltable with said table and overlying both the paper table and the support, and an index carried by the paper table.

Signed at New York city, in the county of 60 New York and State of New York, this 30th day of April, 1917.

LEWIS C. MYERS.
